FOUNDATION GARMENT

Max Kahn, Cedarhurst, N. Y.

Application November 16, 1933, Serial No. 698,335

6 Claims. (Cl. 2—37)

This invention relates to foundation garments and has for an object to provide an improved construction which will snugly fit and mold the body of the wearer while presenting means whereby the garment may be readily removed without injuring the stays or other parts thereof.

Another object of the invention is to provide an improved foundation garment adapted to extend from substantially the waistline downwardly over the hips, and wherein the panels are so formed that elastic zones are presented which will stretch circumferentially and other zones longitudinally of the garment, with the connecting edges formed so that they will stretch longitudinally.

A still further object of the invention is to provide a foundation garment adapted to extend from the waistline downwardly, the structure including a disengageable stiffening panel at the front with elastic panels forming the body of the garment, whereby when the disengageable panel has been disengaged the other panels may be rolled readily so as to move the garment downwardly over the hips without mutilating or in any way injuring the stiffening panel.

In the accompanying drawing—

Figure 1 is a perspective view of a foundation garment disclosing an embodiment of the invention, the same being shown on a figure;

Figure 2 is a view similar to Figure 1 but showing the garment partly removed and illustrating how the same may be rolled during the removing action;

Figure 3 is a rear view of the foundation garment shown in Figure 1, the same being illustrated on a figure;

Figure 4 is an enlarged fragmentary view partly in section illustrating how the reinforcing panel or shield is connected in place;

Figure 5 is a view from inside of the front of the garment, the same illustrating the position and arrangement of the protecting shield or panel;

Figure 6 is a sectional view through Figure 5 on the line 6—6;

Figure 7 is a perspective sectional view through Figure 5 on the line 7—7, the same being on an enlarged scale;

Figure 8 is a plan view of part of the rear panel shown in Figure 3, together with two of the side panels, illustrating how the panels are cut so as to allow elasticity along the seams.

Referring to the accompanying drawing by numerals, 1 indicates the front panel which is divided into the upper section 2 and lower sec-

tion 3. The upper section 2 is principally made from inelastic material and will not stretch substantially in any direction. Section 3 of panel 1 is adapted to stretch freely circumferentially but not longitudinally of the garment. Connected to panel 1 by the seams 4 and 5 are front side panels 6 and 7 which are stretchable circumferentially but substantially nonstretchable longitudinally. At the rear (Fig. 3) the rear panel 8 is formed with an upper section 9 and a lower section 10, the lower section being freely stretchable longitudinally of the garment as indicated by the arrow 11, but substantially nonstretchable circumferentially.

The reverse is true of section 9, which is stretchable circumferentially of the garment but substantially nonstretchable longitudinally of the garment. Stiffening pockets 12 and 13 are arranged in section 9 and extend diagonally from the respective ends of the seam 14 which connects the sections 9 and 10. Stiffening members are preferably arranged in these pockets and give the desired support without in any way preventing the stretching action circumferentially of the garment. Seam 14 is made in a slight V so as to be diagonal in respect to both sections 9 and 10, whereby the cloth along this seam will stretch circumferentially both above and below the seam for a short distance.

The seams 15 and 16 connect the respective rear side panels 17 and 18 with the rear panel 8, there being two rear side panels and two front side panels. All the side panels are stretchable freely circumferentially of the garment but substantially nonstretchable longitudinally. However, the seams 15 and 16 are stretchable by reason of the construction of the parts. This construction is shown more in detail in Fig. 8 from which it will be seen that the rear side panel 18 is rounded at the respective points 19, 20, 21 and 22. The rear panel 8 is also rounded at points 23 and 24. The opposite edge of the rear panel is formed in a similar manner so that the description and showing in Fig. 8 will refer to both edges. It will be understood that when the seam 16 is formed, the edges 19 and 23 are brought together, and in a similar way the edges 21 and 24 are brought together, and then stitching applied. By reason of the fact that the edges when secured together will be somewhat on the bias, stretching of the sections longitudinally of the garment near the seam will be permitted.

The same is true for the entire panel so that the respective seams 15 and 16 may stretch longitudinally, thus permitting the rear section 17

to freely function. If the parts were not made as shown in Fig. 8 the rear panel 8 could not function freely along or adjacent the seams, because it would be held against longitudinal stretching 5 by the fact that the panel 8 would not stretch longitudinally. However, by making the adjacent edges curved there is a diagonal positioning of the fabric which will allow ample stretching along the respective seams 15 and 16 to 10 permit the entire panel 10 to function freely so as to take care of any bending action of the person wearing the garment. The stretching of section 9 in the rear panel circumferentially is very important as it augments the stretching of 15 the front and rear side panels, so that the garment may be pulled over the feet and hips and to the proper position as shown in Fig. 1. The stretching of the waistline part of the garment, namely, the upper edge, must be sufficient to 20 allow it to pass over the hips. Also, the parts must be arranged so that after passing over the hips it will contract sufficiently to snugly fit and support the body at the waistline. This is necessary and at the same time it is desirable that 25 section 10 of panel 8 be stretched longitudinally along with the seams 15 and 16 so that the wearer of the garment may readily sit down or bend without the garment riding up.

In addition to the parts just described it is desirable to have a stiffening and reinforcing structure at the front. Where stiffening and reinforcing steels or other members are used at the front, a side opening must usually be provided in order that the garment may be slid over the 30 hips as it is applied and removed. In the present invention this is not necessary as the garment may be formed as just described and readily moved over the hips when being applied or removed, and when in place properly supporting 35 not only the hips and lower part of the body but also the body at and adjacent the waistline. However, to provide additional stiffening at the front an auxiliary stiffening panel or shield 25 is provided. This shield or panel is preferably 40 stitched to the section 2 by the line of stitching 26. Aside from the line of stitching 26 the panel or shield 25 is free of the remainder of the garment. Disengageable fastening means 27 are 45 provided for disengageably connecting the upper edge of the panel or shield to the upper edge of section 2 of panel 1. The shield 25 is provided with any desired number of reinforcing steels 28 50 arranged in suitable pockets 29. This provides a desired support directly at the front where the body has a tendency to bulge out slightly. If 55 the shield 25 was stitched or fastened firmly on all sides to section 2 of panel 1 and the garment could not be readily applied or removed, because it could not be rolled as indicated in Fig. 2. 60 When the garment is in place, as shown in Fig. 1, and it is desired to remove the same, the snap-fasteners 27 are disengaged and then the upper edge of the garment rolled once or more times and gradually pushed over the hips, the shield 25 65 remaining straight and therefore uninjured. If the steels 28 were rolled along with the remaining part of the garment they would break or become so bent as to be unusable. In this way a desired stiffening shield may be utilized while 70 at the same time presenting a garment which may be rolled at the upper part to be readily applied or removed.

I claim:—

1. A foundation garment comprising a body 75 formed with elastic members, said body being of

greater diameter at the center than at each end, the upper end being of a diameter to normally fit snugly the waistline of the person wearing the garment and stretchable sufficiently to pass over the hips, said upper part of the garment being capable of being rolled downwardly when the garment is being removed, and a reinforcing shield at the center of the front, said shield being connected to the front of the body at a point spaced downwardly from the upper edge, disengageable fastening means for securing the upper edge of the shield to the upper edge portion of the body, and stiffening means carried by said shield, the disengagement of the shield at the upper part from the body permitting the body to be rolled downwardly without bending the shield, whereby the body may be readily removed from the person wearing the garment. 10 15

2. A foundation garment comprising a body elastic substantially throughout with a substantially inelastic section at the upper part of the front, and a reinforcing and bracing shield arranged interiorly of the front, means connecting the lower edge of the shield to the body at a point spaced downwardly from the upper edge of the body, and disengageable securing means for connecting the upper edge portion of the shield to the upper edge portion of the body, and stiffening stays carried by said shield, said disengageable fastening means adapted to be disengaged before 30 the upper portion of the garment is rolled for removing the garment. 20 25

3. A foundation garment comprising a body shaped so that the top and bottom will be of substantially the same diameter, said body at the 35 front having an inelastic panel extending from the top downwardly, and a circumferentially stretchable elastic section extending from the bottom of the body to the lower edge of the first mentioned section, a bracing and stiffening shield arranged interiorly of the front panel, means for securing the shield to the front panel at a distance below the upper edge of the front panel, disengageable means for securing the upper edge portion of the shield to the upper edge portion 40 of the front panel, a pair of circumferentially elastic members forming each side of said body, two of said members being connected to said front panel, and a pair of rear side sections connected to the other two front elastic sections, and a rear panel connected to the rear side sections, said rear panel having an upper portion 45 formed of resilient material stretchable circumferentially of the garment, and a lower portion extending from the bottom of the first mentioned portion to the bottom of the garment and stretchable longitudinally of the body but not circumferentially thereof, whereby the body of the person wearing the garment may readily bend back and forth, forwardly and rearwardly freely while 50 having a comparatively stiff front support. 55 60

4. A foundation garment comprising a body having a front panel with an upper section extending from the top downwardly, and a circumferentially stretchable section extending from the top section downwardly to the bottom edge of the garment, a reinforcing shield arranged interiorly of the first mentioned section to stiffen the same and brace the body, means for connecting said reinforcing section at the lower edge permanently to said body at a distance spaced downwardly from the upper edge of the body, disengageable fastening means for connecting the upper edge portion of the reinforcing member to the upper edge portion of the body, a pair of cir- 70 75 80 85 90

- 5 cumferentially elastic members forming each side of the body, two of said side members being connected to said front panel, and a rear panel connected to the other two side elastic sections, 5
10 said rear panel having an upper section occupying substantially one-third of the rear panel, said section being arranged at the top of the rear panel and stretchable circumferentially of the garment, and a lower section extending from the first mentioned section to the bottom of the garment and stretchable longitudinally of said body, whereby the body of the person wearing the foundation garment may readily bend back and forth and forwardly and rearwardly freely while 10
15 having a comparatively stiff front support, said body at the upper portion being capable of being rolled during the removal of the garment after said disengageable fastening means have been disengaged. 15
20 5. A foundation garment including a body having a front panel, a rear panel stretchable and elastic substantially longitudinally but substantially unstretchable circumferentially of the garment and a side panel structure forming the respective sides of the garment and elastic and stretchable circumferentially but substantially unstretchable longitudinally of the garment so that the hips are resiliently confined while the front of the body of the person is supported and the rear of the body of the person is permitted 20
25
- free movement without shifting of the garment, means for connecting the adjacent edges of the panels together, the edges of the rear panel and the adjacently connected edges of the side panel structure being cut along curved lines, the curved lines extending from an intermediate portion of the edges towards the ends thereof so that the edges are connected on the bias and the connected edges between the rear panel and the side panel structure will be stretchable longitudinally of the garment. 25
6. A foundation garment including a body having a front panel, a rear panel stretchable one way and substantially longitudinally but substantially unstretchable circumferentially of the garment and a side panel structure forming the respective sides of the garment and stretchable one way circumferentially but substantially unstretchable longitudinally of the garment. means for connecting the adjacent edges of the panels together, the edges of the rear panel and the adjacently connected edges of the side panel structure being cut along lines which curve from the intermediate portions of the edges towards the ends thereof, the cutting of the edges along the curved lines providing bias cuts of the material along said curved portions so that the material along the connected edges will be stretchable longitudinally of the garment. 30
